ACCESSORY CONSOLE FOR MOTORCYCLES

Tommy W. Dixson, 1509 W. Willetta,
Phoenix, Ariz. 85007

Filed Feb. 24, 1975, Ser. No. 552,301

Term of patent 14 years

Int. Cl. D12—11

U.S. Cl. D12—114

FIG. 1 is a top, left, front perspective view of an accessory console for motorcycles showing my new design;

FIG. 2 is a bottom, left, rear perspective view thereof; and

FIG. 3 is a right side elevational view thereof.

I claim:

The ornamental design for an accessory console for motorcycles, as shown.
